DEEP WELL PUMP

William L. Connor, Los Angeles, Calif., assignor
to Fluid Packed Pump Company, Whittier,
Calif., a corporation of Nevada

Application October 14, 1935, Serial No. 44,819

9 Claims. (Cl. 103—187)

My invention relates to reciprocating pumps, and is directed to a pump construction especially applicable to deep well installation, the present disclosure being a specific form of the invention 5 described in my co-pending application, filed on the same date, serially numbered 44,818, and entitled "Deep well pump".

The principal object of my invention is to provide a pump that will deliver an exceptionally 10 large quantity of fluid for a given length of stroke.

The engineer attacking the problem of adequate pumping from the exceedingly deep wells that are becoming more numerous in current oil 15 production, is confronted by at least four important limiting considerations. These considerations should be given some thought for a proper understanding of the present invention.

First, there is the fact that the cross-sectional area of an oil pump must be confined to the dimensions of the discharge tubing, which, in turn, 20 must be accommodated by the well casing. Of necessity, therefore, the pump itself may be no larger than two or three inches in diameter.

Secondly, the usual power equipment installed 25 at a well provides for a limited length of pump stroke, partly from custom and standards established in pumping wells of moderate depth, and partly because of the greater investment and higher operating cost involved in using equipment for longer pump strokes. The power required to lift the long column of oil in a deep well 30 taxes standard equipment; to increase the amplitude of the pump stroke without reducing the number of strokes per minute may further tax prevailing power equipment as to be impractical, or, at best, to involve serious offsetting losses. For 35 example, it must be borne in mind that increasing the throw of a pump crank increases the acceleration and velocity of the long oil column and 40 string of rods.

The third important consideration is that because of the inordinate weight of the oil column in a deep well, and because of the excessive distance separating the power unit from the pump, 45 resiliency of the string of rods becomes a serious loss factor. This stretch in the pump rods is subtracted from the power stroke at the surface to net the effective stroke at the pump.

Finally, increasing the number of strokes per 50 minute has serious disadvantages. In current practice, it is common, because of the stretch in the rods at a great depth, to use a relatively small pump at a compensating relatively high number of strokes per minute. Two cost factors enter 55 here. In the first place, the more rapidly a pump

operates for a given rate of production, the more wear and the higher the ratio of the cost of pump replacement to production. In the second place, the greater the number of times the string of rods must be stretched for a given quantity of production, the greater the waste of power. 5

The advantages of my invention may be readily understood in the light of the four considerations recited. By providing for increased volume of oil flow per unit length of pump stroke, within the 10 restricted cross-sectional area of well tubing, I compensate for motion lost in the stretch of the rods, and do so without engendering difficulties inherent either in increasing the length of the strokes, or in increasing the rate of the strokes. 15 Standard power equipment may be utilized at customary speeds, and pump replacement will be normal for any given well.

I accomplish increased pump capacity by incorporating two pumping units in tandem in a 20 single pump structure, arranging for one of the pumping units to pump into or through the other pumping unit.

Broadly described, my invention comprises two 25 pump cylinders in telescopic relation adapted for relative movement longitudinally, each cylinder carrying a piston that is effective with the other cylinder, a fluid passage being provided to permit one cylinder to pump either into or through the other cylinder. 30

The recital of other objects, advantages, and features of my invention is, for the purpose of better understanding, reserved for the detailed description to follow. In this disclosure, the principles of my invention, are, for illustration, 35 embodied in a removable type pump.

In the accompanying drawings:

Fig. 1 is a broken elevation, large in section, of my pump installed in a well tubing;

Figs. 2, 3, and 4, taken together, comprise an 40 enlarged axial section similar to Fig. 1;

Fig. 5 is a horizontal section taken on line 45—5 of Fig. 2;

Fig. 6 is a fragmentary axial section indicating a modified construction wherein one of the pump 45 valves is omitted; and

Fig. 7 is a fragmentary axial section indicating how my invention may be modified by adding a bottom discharge valve.

Pump jacket 10 is incorporated in the discharge 50 tubing through which oil is pumped to the surface of the well. Threaded to the bottom of the jacket, as an extension thereof, is standing valve shoe 11, having the usual tapered seat 12 and inwardly disposed annular shoulder 13. From 55

the bottom of the standing valve shoe, a gas anchor plug 14 and tubing (not shown) may extend if desired.

Under normal pumping conditions, an expansion mandrel 15 is removably seated in standing valve shoe 11. Shoulders 16 on the flexible extensions 17 of the mandrel engage the aforementioned annular shoulder 13 of the standing valve shoe.

10 Expansion mandrel 15 supports the stationary parts of my pump, including a lower standing valve generally designated by numeral 18, and a lower inner cylinder 19; while the movable parts of my pump, including an upper outer cylinder 15 20, a tube 21, and travelling valve generally designated by numeral 22, are supported and moved by sucker rod 23.

It will be noted that mandrel 15, together with standing valve shoe 11, forms a seal between, on 20 the one hand, the well-pressure zone below the pump, and outside the pump jacket, and, on the other hand, the tubing-pressure zone within the jacket that is subject to the tremendous weight of the oil column extending to the top of the 25 well.

Standing valve cage 24 is in the form of a coupling in threaded engagement with mandrel 15, and, in the usual manner, is provided with ball guides 25. Suitably secured between cooperating 30 surfaces of the expansion mandrel and valve cage, is a valve seat 26 to receive ball 27. The range of the ball upward is limited by suitable stop 28, the stop being integral with a nipple 29 that is threaded into the upper end of valve cage 24.

35 The upper portion of nipple 29 is threaded for the mounting of stationary inner cylinder 19. Mounted to the top of this cylinder, and serving as a continuation thereof, is a relatively extensive, annular, stationary piston 30 dimensioned to 40 cooperate both with tube 21 and outer cylinder 20 for pumping action.

It is essential, in the operation of my pump, that the annular space 31 below piston 30 and between tube 21 and stationary cylinder 19 be 45 freely vented to the tubing-pressure zone of the well. For this purpose, the wall of the inner cylinder may be provided with suitable vent ports 31a near the lower edge of stationary piston 30, and around and below these ports the periphery 50 of the outer surface of the inner or travelling cylinder may be either cut away longitudinally or reduced in diameter for a sufficient longitudinal distance to extend below the bottom edge of outer travelling cylinder 20 at all positions of the pump, 55 thereby providing a clearance space 32, open at all times.

Connected to the bottom end of sucker rod 23 is the cage 33 of travelling valve 22, the cage having fluid ports 33a. Threaded into the bottom of cage 33 is a suitable nipple 35 that cooperates with the cage to retain a valve seat 36 for ball 37. The lower portion of nipple 35 is reduced in diameter and threaded to receive a spider generally designated by numeral 38, and is further 60 reduced at its lower extremity 39 and cut away to provide a plurality of radially disposed ports 40.

Spider 38 comprises an upper tubular portion 41 threaded on its inner and outer peripheral surfaces, a plurality of integral legs 42, and an 70 integral, lower, restricted ring portion 43. The outer threads of the spider serve for supporting outer travelling cylinder 20.

Tube 21 is provided at the top with an integral, annular shoulder 44, and is dimensioned 75 to fit through ring 43 with shoulder 44 engaging

the ring from above, and with the tube held against the lower end 39 of nipple 35. A liberal clearance is provided between the periphery of the tube and ring 43, and again between annular shoulder 44 and legs 42 of the spider. By virtue 5 of this arrangement, the tube is secured against longitudinal movement but has a substantial degree of lateral freedom.

It will be apparent that the interior of tube 21 is in communication with passage 45 leading to 10 travelling valve 22 and also, by virtue of ports 40 and the spaces between the legs of the spider, is in communication with an annular pump chamber 46 between the tube and outer cylinder 20.

Mounted to the lower end of tube 21 by 15 threaded engagement is a relatively extensive, annular piston 47 (Fig. 3) dimensioned to cooperate with lower cylinder 19 for pumping action. In the preferred form of my invention, this piston serves as an extension of tube 21 and is provided with a lower travelling valve generally designated by numeral 48.

The piston has a reduced portion 51 at its lower end that continues as a plurality of spaced longitudinal fingers 52. These fingers serve as guides for ball 53, the upper limit of the ball movement being determined by a stop pin 54 spanning the piston. Threaded to reduced portion 51 of the piston is a suitable cylindrical member 55 that serves as an extension of the piston and also cooperates with the ends of fingers 52 to retain valve seat 56.

The purpose of the lateral freedom provided in the mounting of tube 21 will now be apparent; by virtue of the clearance provided, the tube will 35 automatically adjust itself to any inaccuracy in the boring and machining of the stationary piston.

It is contemplated that, in a typical pump, each of the two pistons will be approximately three 40 feet long, and that the pump will be dimensioned for approximately a six-foot stroke.

The drawings indicate the disposition of the various parts of the pump at or near the bottom of the stroke. As sucker rod 23 lifts travelling 45 cylinder 20 on the upward stroke of the pump, upper travelling valve 22 will close under pressure from the oil column in the well tubing. As upper travelling valve 22 retreats from stationary piston 30, annular pump chamber 46 within the travelling 50 cylinder will expand; and as travelling piston 47 simultaneously retreats from the bottom end of standing cylinder 19, lower pump chamber 57 will likewise expand. On this movement, pressure from the well will open lower standing valve 55 18, and oil from below the pump will flow under well pressure into lower pump chamber 57, and oil likewise will flow through tube 21, ports 40, and between legs 42 of the spider into upper pump chamber 46.

On this upward movement of the pump, annular space 31 will contract, the oil therefrom escaping freely into the tubing-pressure zone by virtue of ports 31a and clearance space 32.

As travelling piston 47 approaches stationary 65 piston 30, it cuts off ports 31a, thereby restricting flow from annular space 31 to produce a cushioning effect at the top of the stroke.

On the downward stroke, standing valve 18 will close; oil from lower pump chamber 57 will 70 be expelled through lower travelling valve 48, tube 21 and ports 40 leading from the annular space 46 into passage 45; and the oil from passage 45, forcing open traveling valve 22, will be discharged into the well tubing.

On this downward stroke, annular space 31, expanding in volume, will have received oil freely from the tubing-pressure zone.

5 My pump may be regarded as consisting of two interconnected pumping units: the upper pumping unit, represented by chamber 46, comprises travelling cylinder 20, travelling valve 22, the exterior of tube 21, and stationary piston 30; the lower pumping unit, represented by pump chamber 51, comprises standing cylinder 19, travelling piston 47, and lower standing valve 18.

10 It will be noted that it is possible for me, in effect, to arrange two pumps in tandem to operate within the confines of well tubing, because, by virtue of tube 21, I provide for communication between the two pumps, so that on the intake stroke, the upper pump may draw from the lower pump, and, on the discharge stroke, the lower pump may deliver oil into or through 15 the upper pump.

15 Because two pumping units are provided in tandem and connected to the same sucker rod for simultaneous operation, my pump will deliver a greater volume of fluid per unit length of stroke than any other reciprocating pump heretofore employed in deep wells. A simple plunger pump of the same inside diameter as the outer travelling tube would deliver, in one 20 stroke, a volume of oil equal to the length of the stroke times the cross-sectional area of the standing tube; whereas my pump will deliver the same volume plus the stroke times the cross-sectional area of annular pump chamber 46.

25 Provided the well produces enough oil to work the pump at capacity, on the down stroke when standing valve 18 is closed, the column of oil in the tubing-pressure zone will remain substantially stationary while the moving parts of the pump slip through the fluid, the fluid escaping from the pump through travelling valve 22. On the up stroke of the pump when travelling valve 22 is closed, the pump moving upward displaces in the tubing around the pump a volume equal to the volume of oil previously 30 discharged from the pump on the down stroke, such displacement causing the oil column to move towards the surface of the well.

35 In pumping to capacity fluid that is relatively free of gas, lower travelling valve 48 will remain open substantially all the time, because, on the upward stroke, the upper pumping unit will be expanding to receive oil through tube 21, and, on the downward stroke, the lower pumping unit will be contracting to expel oil through 40 tube 21 in the same direction. It is apparent, then, that this intermediate valve may be omitted entirely.

45 One modification of my pump consists simply in omitting this valve, as indicated in Fig. 6, in which corresponding parts are given corresponding numbers. In the figure, travelling piston 60 is shown without a valve.

50 While this intermediate valve may be omitted, I prefer to include it for two reasons: because 55 it is believed that, where a high ratio of gas to fluid is being pumped, the valve may serve to break up the gas column within the pump and thereby facilitate compression of the gas for discharge from the pump; secondly because by 60 providing three valves, I have a pump that will continue to function when any one of the three valves fails. If the intermediate valve fails to close, the volume delivered by the pump will not ordinarily be affected; if the upper travelling 65 valve fails to close, the lower pumping unit will

continue to function; if the lower standing valve fails to close, the upper pumping unit will continue to function.

70 A second modification of my invention, as indicated by Fig. 7, corresponding numbers being used to indicate corresponding parts, is distinguished by the addition to the lower pumping unit of a bottom discharge valve generally designated by the numeral 61.

75 In this third form of my invention, the lower discharge valve comprises a T shaped tube 62 spanning standing cylinder 19, the horizontal portion of the tube forming two ports 63 in the periphery of the standing cylinder. A suitable bushing 64 screwed into the bottom of the vertical portion 65 of the T secures in place a valve seat 66 to receive ball 67. A suitable depending lug 68 within the T serves as a stop for ball 67.

80 On the upward stroke of the pump, this third form of my invention functions in the same manner as the first two forms, lower discharge valve 61 being closed. On the down stroke of the pump, however, fluid from the lower pumping unit may be discharged entirely through valve 61, each pumping unit discharging independently of the other. Obviously, in that case, oil would flow through tube 21 only on the up stroke of the pump.

85 In the removable type of deep well pump here shown, the pump is removed by simply drawing sucker rod 23 upward beyond the usual range of the pump stroke, until travelling piston 47 engages stationary piston 30. The force upward exerted by the sucker rod will then be transmitted to the stationary parts of the pump through tube 21, and expansion mandrel 15 may readily be jarred out of engagement with shoulder 16 of standing valve shoe 11. The pump assembly may then be readily lifted to the surface of the well.

90 It is apparent, then, that, while it is desirable to restrict the cross-sectional area of tube 21 for the purpose of increasing the cross-sectional area of annular pump chamber 46 to 45 attain maximum pump capacity, the limit to which the cross-sectional area of tube 21 may be restricted will be determined by two considerations: the fact that the tube must be large enough to accommodate, without serious friction, the required flow of fluid through the tube; and the fact that the tube itself must be of sufficient size and strength to accommodate strain incidental to engaging the pump from the standing valve shoe and transporting the pump 50 to the surface of the well. Because of this latter consideration, I prefer to use alloy steel for tube 21.

95 Restricting the cross-sectional area of tube 21, reduces the residual volume of the pump, 60 i. e., the cubical content of the pump at the end of the discharge stroke. When the residual volume of a pump is relatively large, the efficiency of the pump may be seriously impaired by the presence of excessive gas in the oil; because 65 the work of the pump will be devoted largely to merely compressing the gas within the pump. It is believed that my pump has less residual volume than any other pump of the same size employing telescoping pump cylinders. Since 70 my pump expands on the intake stroke to a relatively large volume, and since the efficiency of a pump in the presence of gas is favored by a high ratio between this expanded volume and the residual volume, my invention may be used 75

profitably where the presence of a large percentage of gas in a deep well would preclude economic operation of another type of pump.

For the purpose of complete disclosure and to illustrate the principles involved, I have described my invention as embodied in a deep well pump of the removable type. It is obvious that the invention may be applied to pumps of other types for other purposes, and it will be apparent that my invention may be subject to a wide range of material modification and change without departing from the principles involved. I reserve the right to all such modification and change that come within the scope of my appended claims.

Having described my invention, I claim:

1. A pump having in combination: a lower pump cylinder adapted to be stationary with its lower end extending into the well-pressure zone of a well, the balance of the pump to be surrounded by tubing pressure from above the pump; a valve-controlled intake port in said lower end of the cylinder; an upper pump cylinder adapted to reciprocate telescopically over said lower cylinder; a valve-controlled discharge port at the upper end of the upper cylinder; a downwardly extending tube fixedly mounted within the upper cylinder, the upper end of said tube communicating with the interior of the upper cylinder; an annular piston mounted on the tube to cooperate with the lower cylinder for pumping action; and a second annular piston mounted on the upper end of the lower cylinder to cooperate with said tube and upper cylinder for pumping action, the wall of the lower cylinder below the second annular piston being reduced in diameter to provide a clearance between the inner cylinder and the outer cylinder, and said wall being provided with ports near said second piston for the purpose of venting the annular space between the two pistons.

2. A pump having in combination: an inner pump cylinder; an outer pump cylinder telescopically associated with the inner pump cylinder; a valve-controlled intake port associated with the inner pump cylinder; a valve-controlled discharge port associated with said inner cylinder; a valve-controlled discharge port associated with said outer cylinder; a tube fixedly mounted in the outer cylinder extending through the outer cylinder towards the inner cylinder, said tube communicating with the interior of the outer cylinder and with said second mentioned discharge port; an annular piston mounted on the tube to cooperate with the inner cylinder for pumping action; a second annular piston mounted on the inner cylinder to slidably embrace said tube and to cooperate with the outer cylinder for pumping action; and a check valve associated with said tube to prevent flow therein towards said inner cylinder.

3. A pump having in combination: an inner pump cylinder; an outer pump cylinder telescopically associated with the inner pump cylinder; a valve-controlled intake port associated with said inner pump cylinder; a valve-controlled discharge port fixedly attached to said inner cylinder; a valve-controlled discharge port associated with said outer cylinder; a tube fixedly mounted in the outer cylinder, said tube communicating with the interior of the outer cylinder and said second mentioned discharge port; an annular piston mounted on the tube to cooperate with the inner cylinder for pumping action; and a second annular piston mounted

on the inner cylinder near the inner end thereof to slidably embrace said tube and to cooperate with the outer cylinder for pumping action.

4. A pump having in combination: an inner pump cylinder; an outer pump cylinder telescopically associated with the inner pump cylinder; a valve-controlled intake port associated with said inner pump cylinder; a valve-controlled discharge port associated with said outer cylinder; a tube fixedly mounted in the outer cylinder, extending through the outer cylinder towards the inner cylinder, said tube communicating with the interior of the outer cylinder; an annular piston mounted on the tube to cooperate with the inner cylinder for pumping action; and a second annular piston mounted on the inner cylinder to have substantially sealing contact both with the tube and with the outer cylinder for pumping action, thereby forming two disconnected annular chambers, one of said chambers communicating with both said valves, the other annular chamber being vented directly to the exterior of the pump.

5. A pump having in combination: a lower pump cylinder adapted to be stationary with its lower end extending into the well-pressure zone of a well, the balance of the pump to be in the tubing-pressure zone extending above the pump; a valve-controlled intake port in said lower end of the cylinder; an upper pump cylinder adapted to reciprocate telescopically over said lower cylinder; a valve-controlled discharge port at the upper end of the upper cylinder; a tube fixedly mounted within the upper cylinder extending downward, the upper end of said tube communicating with the interior of the upper cylinder; an annular piston mounted on the tube to cooperate with the lower cylinder for pumping action; and a second annular piston mounted on the inner cylinder to have substantially sealing contact both with the tube and with the outer cylinder for pumping action, thereby forming an annular chamber between the two pistons out of communication with the rest of the pump, said chamber being vented directly to the exterior of the pump in said tubing pressure zone.

6. A pump having in combination: an inner pump cylinder; an outer pump cylinder telescopically associated with the inner pump cylinder; a valve-controlled intake port associated with said inner pump cylinder; a valve-controlled discharge port associated with said outer cylinder; a tube fixedly mounted in the outer cylinder, extending through the outer cylinder towards the inner cylinder, said tube communicating with the interior of the outer cylinder; an annular piston mounted on the tube to cooperate with the inner cylinder for pumping action; and a second annular piston mounted on the inner cylinder to have substantially sealing contact both with the tube and with the outer cylinder for pumping action, thereby forming an annular chamber between the two pistons out of communication with the rest of the pump, said chamber being vented to the exterior of the pump.

7. A pump having in combination: a lower pump cylinder adapted to be stationary with its lower end extending into the well-pressure zone of a well, the balance of the pump to be in the tubing-pressure zone extending above the pump; a valve controlled intake port in said lower end of the cylinder; an upper pump cylinder adapted to reciprocate telescopically over said lower cylinder; a valve-controlled discharge port at the

- upper end of the upper cylinder; a tube fixedly mounted within the upper cylinder extending downward, the upper end of said tube communicating with the interior of the upper cylinder; a check valve associated with said tube to prevent downward flow therein; an annular piston mounted on the tube to cooperate with the lower cylinder for pumping action; and a second annular piston mounted on the inner cylinder to have substantially sealing contact both with the tube and with the outer cylinder for pumping action, thereby forming an annular chamber between the two pistons out of communication with the rest of the pump, said chamber being vented to the exterior of the pump. 5
9. A pump having in combination: a lower, inner pump cylinder; an outer, upper pump cylinder telescopically associated with the inner pump cylinder; a valve-controlled intake port associated with said inner pump cylinder; a valve-controlled discharge port associated with said outer cylinder; a tube fixedly mounted in the outer cylinder, extending towards the inner cylinder, said tube communicating with said discharge port; a port in the tube adjacent its upper end communicating with the interior of the outer cylinder; an annular piston mounted on the tube to cooperate with the inner cylinder for pumping action; a second annular piston mounted on the inner cylinder to have substantially sealing contact both with the tube and the outer cylinder for pumping action, thereby forming two disconnected annular chambers, one of said chambers communicating with both said valves, the other chamber being vented to the exterior of the pump; and a check valve associated with said tube to prevent flow therein towards said inner cylinder. 10
8. A pump having in combination: a lower, inner pump cylinder; an outer, upper pump cylinder telescopically associated with the inner pump cylinder; a valve-controlled intake port associated with said inner pump cylinder; a valve-controlled discharge port associated with said outer cylinder; a tube fixedly mounted in the outer cylinder, extending towards the inner cylinder, said tube communicating with said discharge port; a port in the tube adjacent its upper end communicating with the interior of the outer cylinder; an annular piston mounted on the tube to cooperate with the inner cylinder for pumping action; a second annular piston mounted on the inner cylinder to have substantially sealing contact both with the tube and the outer cylinder for pumping action, thereby forming two disconnected annular chambers, one of said chambers communicating with both said valves, the other chamber being vented to the exterior of the pump; and a check valve associated with said tube to prevent flow therein towards said inner cylinder. 15
